CLAIM

The ornamental design for an vehicle body, as shown and described.

DESCRIPTION

FIG. 1 is a front perspective view illustrating an vehicle body constructed in accordance with the teachings of the present invention.

FIG. 2 is a rear perspective view thereof.

FIG. 3 is a left side view thereof, it will be understood that the side opposite to that shown is a substantial mirror image thereof; and,

FIG. 4 is a front view thereof.

It will be understood that the broken line showing of the wheels, tires and tailpipes throughout the drawings is for illustrative purposes only and forms no part of the subject invention.
